ATTORNEY.

UNITED STATES PATENT OFFICE.

CHRISTIAN L. SAAL, OF PATERSON, NEW JERSEY, ASSIGNOR OF ONE-FOURTH TO
WILLIAM LAESSIG, OF PATERSON, NEW JERSEY.

WINDING MACHINE.

Application filed April 29, 1927. Serial No. 187,585.

This invention relates to winding machines in which the cores for the wound packages being formed are revolvably supported in contacting relation to but so as to be movable, as upwardly from rotary driving means having its axis horizontal. It is known in these machines to provide individual ejectors, arranged opposite the respective wound masses of the packages being formed, for automatically causing the packages to be shifted clear of the driving means and stop their rotation when they have been filled or wound to a given diameter. Heretofore, however, when it was desired to change the diameter of the packages produced in these machines it was necessary to adjust individually all of the mentioned ejectors. My present invention contemplates avoiding this and making only one adjusting operation necessary. It also contemplates the provision of means whereby the attendant can determine at a glance just what diameter and hence yardage the produced packages will have. In my machine I further use an eccentric to serve as an ejector and in order that it may be made to operate with equal efficiency in whatever position it is adjusted I provide in a novel way for further adjusting thereof.

30 In the drawing,

Fig. 1 is a side elevation of as much of a winding machine as embodies the present invention;

Fig. 2 is a plan thereof; and

35 Fig. 3 is a sectional view through one of the packages.

The frame 1 includes the usual series of projecting brackets 2 formed with guideways 3 for the package trunnions and top notches 4 back of the guideways to receive said trunnions in the rest or idle positions of the packages. The package driving means takes the usual form, to wit, a suitably driven horizontal shaft 5 journaled in the frame beneath all the brackets and driving wheels 6 on the shaft to contact with the cores of the packages. The core of each package to be formed may consist, as usual, of two parts, a spindle 7 whose ends afford the mentioned trunnions and having a whirl 8 which actually receives the driving contact of the corresponding wheel 6, and a spool 9 removably fitted on the spindle and on which the winding of the thread or yarn 10 is directly effected.

guide rail, suitably caused to traverse in brackets 11, and 12 its thread-guides. It will be understood that the yarn or thread comes from any suitable supply, as swifts free to rotate in the frame and not herein shown.

In suitable bearings 13 on the frame I journal a horizontal rock-shaft 14, which protrudes from the frame at one end and there has a handle 15. This shaft has affixed to it by set-screws 16, so as to be adjustable around it, a series of arms 17, one for and arranged to project under the portion (here the spool) of each core where the windings are formed. In each arm, with its axis horizontal, is a bearing member or stud 18, secured by a nut 19 screwed thereon and a shoulder 20 coacting to clamp the arm; there is a longitudinal slot 21 in the arm permitting adjustment of the stud across the arc in which the bearing member moves when the support afforded by the rock-shaft and its arms is rotatably adjusted. On the stud is an ejector here in the form of an eccentric 22 which is free to rotate and is normally held by gravity in that position where its greatest radius is below the bearing member.

It will be understood that when the rock-shaft is turned one way or the other it is held in some way in the new position, as by the gearing hereinafter described. Turning the arm one way or the other raises or lowers all the ejectors simultaneously.

Thus by a single adjusting operation the extent to which the winding of all the packages may proceed is determined, it being understood that whenever any package attains that diameter at which it obtains contact with its ejector the latter by the traction is rotated, elevating one end of the package clear of the driving wheel and causing the corresponding trunnion to come to rest in its notch 4.

A dial plate 23 is secured to the end of the machine and has a dial 24 with suitable indices thereon indicating yardage, for example, and with reference to this dial is movable a pointer 25 pivoted in the dial plate and connected by gearing 26, journaled in the dial plate, with the shaft 14. By this means the attendant can readily determine what yardage each spool will attain before stopping of its rotation will occur.

When the ejection occurs the eccentric should be certain of performing its part in causing the package to move over into the notch 4 representing its rest or idle position, 5 due to the rotating spool then rolling on the eccentric toward such position. To make this possible and yet apply the invention to machines in which the rotating or working position of the packages may vary 10 horizontally inward or outward (in Fig. 1, right or left) I provide for the mentioned adjustment of stud 18 (and hence the eccentric) in the slot 21, or across the arc in which the stud moves with arm 17.

15 Having thus fully described my invention, what I claim is:

1. In combination, a frame, rotary driving means therein having its axis substantially horizontal, the frame having means for supporting the cores of the packages to be formed in contacting relation to but so as to be movable from the driving means, a 20 row of ejector devices arranged to be engaged by the peripheries of the wound 25 masses of the respective packages in the winding thereof and on such engagement shift the packages away from the driving means, and a common support for all the 30 ejectors adjustable in the frame to move the ejectors simultaneously toward or from the packages.

2. In combination, a frame, rotary driving means therein having its axis substantially horizontal, the frame having means for supporting the cores of the packages to be formed in contacting relation to but so as to be movable from the driving means, a 35 row of ejector devices arranged to be engaged by the peripheries of the wound 40 masses of the respective packages in the winding thereof and on such engagement shift the packages away from the driving means, and a common support for all the 45 ejectors adjustable in the frame around an axis substantially parallel with the first-named axis to move the ejectors simultaneously toward or from the packages.

3. In combination, a frame, rotary driving means therein having its axis substantially horizontal, the frame having means for supporting the cores of the packages to be 50 formed in contacting relation to put so as

to be movable from the driving means, a 55 row of ejector devices arranged to be engaged by the peripheries of the wound 60 masses of the respective packages in the winding thereof and on such engagement shift the packages away from the driving means, a common support for all the ejectors 65 adjustable in the frame to move the ejectors simultaneously toward or from the packages, and coacting dial and pointer members one of which is fixed and the other connected to move with said support on the adjusting thereof.

4. In combination, a frame, rotary driving means therein having its axis substantially horizontal, said frame having means for supporting the core of a package to be formed in superposed relation to but so as to be movable upwardly from the driving means, a 70 freely revoluble eccentric having its axis substantially parallel with the first-named axis and arranged to be under and to be engaged by the periphery of the wound mass 75 of the package in the winding thereof, a support adjustable in the frame around an axis substantially parallel with the first-named axis to move the eccentric toward or 80 from the package, and a bearing member for said eccentric adjustable in the support across the arc in which said member moves on adjustment of the support, said eccentric on engagement therewith of the package being adapted to elevate the same and the 85 frame having means thereupon to receive and hold the package elevated.

5. In combination, a frame, rotary driving means therein having its axis substantially horizontal, the frame having means for supporting the cores of the packages to be formed in contacting relation to but so as to be moved from the driving means, a row of ejector devices arranged to be engaged by the peripheries of the wound masses on 90 the respective packages in the winding thereof and on such engagement shift the packages away from the driving means, a shaft extending parallel with said axis and 95 adjustable in the frame around its own axis, 100 and arms extending from said shaft and respectively carrying said devices.

In testimony whereof I affix my signature.
CHRISTIAN L. SAAL.
